PATCH

Earl Bullis, Amsterdam, and Max Jacobson,
Johnstown, N. Y.

Application October 15, 1934, Serial No. 748,404

2 Claims. (Cl. 138—98)

This invention relates to an improved mending patch and seeks, among other objects, to provide a device of this character embodying a sealing disc of soft material which, when the patch is tightened to locked position, will be fully enclosed by a depending flange on the head of the device so that said sealing disc will be effectually protected.

Another object of the invention is to provide 10 a mending patch wherein the head is formed with a depending flange so that reinforcement for the circumferential edge will be provided.

A further object of the invention is to provide 15 a mending patch wherein the flange employed will prevent bending up of the head with consequent mutilation of the sealing disc.

A still further object of the invention is to provide 20 a device of this character which may be manufactured cheaply and which may be installed with the utmost facility.

And a still further object of the invention is to provide 25 a mending patch, the sealing disc of which will uniformly engage the surface to be patched so that leakage will be prevented.

It is thought that a reading of the following 30 description will disclose other and incidental objects not specifically pointed out hereinabove.

Referring to the drawing forming a part of 35 our application:

Figure 1 is a vertical sectional view on the line 1—1 of Figure 2, and looking in the direction indicated by the arrows.

Figure 2 is a top plan view of our improved 40 mending patch.

Figure 3 is a vertical sectional view showing a slightly modified form of the device.

Figure 4 is a vertical sectional view showing another modified form of the invention.

Figure 5 is a top plan view showing a further 45 modification of the device.

Figure 6 is a vertical sectional view on the line 6—6 of Figure 5, looking in the direction indicated by the arrows.

Figure 7 is a vertical sectional view illustrating 50 a still further modification of the invention.

Referring now more particularly to the accompanying drawing forming a part of our application, and wherein like numerals of reference 55 designate like parts throughout the description, the numeral 1 indicates a head which is preferably formed from light weight sheet metal and, as shown in Figure 2, is circular in plan. The head is provided at its rim with a depending flange 2. Mounted axially of the head 1 is a stud 3 which is locked in place on the head and is provided

with an externally threaded free end portion 4, which end portion is adapted to receive a nut 5. Normally seated beneath the head 1 and within the confines of the flange 2, is a sealing disc or washer 6 which is formed of cork or some other suitable soft material.

As shown in Figure 1, the device is mounted on a surface or wall 7 which has been punctured, as shown at 8. When properly mounted, the stem 3 extends through the puncture 8 and said puncture is closed at its lower side by a washer 9. The nut 5 is then tightly screwed upon the threaded portion 4. When this is done the sealing disc will be effectually clamped against the wall or surface to be patched so that leakage through the puncture past the patch will be prevented.

As best seen in Figure 1, when the patch has been clamped to locked position, as above described, the rim of the depending flange 2 will engage the wall 7 and close the head so that mutilation of the sealing disc, which might be caused by a sharp object coming in contact with the edge thereof, will be prevented. Furthermore, the depending flange 2 provides reinforcement for the head and also tends to prevent said head 25 from being bent up by contact with a sharp object, such as a knife or the like.

Referring now to the modification of the invention as shown in Figure 3 of the drawing, the numeral 10 indicates the head, which is slightly 30 frusto conical in vertical cross section. The head is provided with a depending flange 11 and a stem 12 which extends through a wall to be patched, such as shown at 13, and is adapted to receive a nut 14, a washer 15 being employed for closing 35 the lower end of the puncture in the wall and permitting the nut 14 to make firm engagement. A sealing disc 16 is employed and is confined beneath the head 10 about the stem 12. As will be observed, the disc does not extend beyond the 40 flange 11 but is confined within the head. In this form of the invention, the frusto conical formation of the head permits a greater amount of pressure being exerted on the flange 11 so that a tight seating of said flange on the wall to be 45 sealed will be permitted. Furthermore, the frusto conical formation of the head prevents said head from bending up when the nut 14 is tightened excessively. The operation of the device is otherwise identical with that of the preferred form. 50

Referring to the modification illustrated in Figure 4 of the drawing, we employ a head 17 which is provided with a stud 18 adapted to extend through a puncture in the surface or wall 19. A washer 20 closes the lower side of the sur- 55

face about the puncture and is held in place by a nut 21. Formed on the head 17 at its circumferential edge is a depending flange 22 which terminates in a relatively short radial flange 23 adapted to overlie the surface 19 when the nut 21 is clamped to a locked position. Disposed beneath the head 17 and within the confines of the flanges 22 and 23 is a sealing disc 24 which is similar in construction to the disc 6 in the preferred form of the invention and is adapted to co-operate with the head and stem for permitting the punctured surface to be effectually patched. The radial flange 23 not only improves the appearance of the device but also facilitates the manufacture thereof as it permits a better gaging of the depth of the head. Aside from the foregoing, the operation of this modification of the invention is identical with that of the preferred form.

20 Referring to the modification of the invention as shown in Figure 6, we employ a head which is indicated in general by the numeral 25. The head is provided with an upwardly pressed semi-circular rib 26 intermediate its radius which defines 25 upper and lower portions 45 and 46, and also a stud 27 which is adapted to project through a surface or wall to be patched. A nut 28 is provided on the stud, as is a washer 29 which washer is adapted to underlie the wall, as shown at 30, and thus provide a firm base against which to tighten the nut 28. Formed on the circumferential edge of the head 25 is a depending flange 31 which terminates in a radial flange 32, which, like the radial flange 23, is adapted to overlie the wall to be patched. A sealing disc 33 is confined within the head 25 and serves effectually to seal the puncture in the wall or surface. The rib 26 provides reinforcement for the head and also serves as a guard, so that when the article to 40 which the patch is secured is being cleaned, the cleaning cloth or scraper will not be permitted to catch under the upper end of the stud 27. Inasmuch as the portion 45 is of greater height than the portion 46, a greater pressure will be exerted on the depending flange 31 and radial flange 32. Aside from this feature, the construction and operation of this modified form of the invention is identical with that disclosed in the modification shown in Figure 4.

50 In the modification shown in Figure 7 of the drawing, we employ a substantially frusto conical head 34 which is provided with a depending flange 35 and a radial flange 36 corresponding to the flanges 31 and 32 in Figure 6. The head is provided with a stud 37 which is provided with an enlarged upper portion or cap 38 carried in a recess 39 formed in the head 34. The stud is adapted to project through the surface or wall to

be patched and a nut 40 is screwed thereon and engaged with a washer 41 for tightly clamping the patch in position. A sealing disc 42 is confined within the head and effectually seals the puncture in the wall so that leakage therethrough will be prevented. In view of the fact that the top portion 38 of the stud is seated in the recess 39, the danger of any object, such as a cleaning implement, catching on the top portion of the head and displacing the patch is largely prevented. 10 Although we have shown in the preferred embodiment of the invention as well as in the modifications, the head as being circular in outline, it should be understood that said head may be of any desired shape. 15

Our improved mending patch, in any of its embodiments, may be manufactured cheaply and may be put into use with the utmost facility.

Having thus described the invention, what we claim is:

20 1. A mending patch including a disc having a marginal flange, a portion of said disc being struck upwardly to form an annular rib spaced from margins of the disc, a stud carried by the disc centrally thereof and adapted to project through an opening to be sealed, said rib surrounding the upper end of the stud, a nut on the lower end of the stud, and a sealing disc disposed against the disc about the stud and being adapted for sealing the opening when the nut is 30 tightened, said rib providing reinforcement for the disc and additional resiliency thereto for creating binding between threads of the stud and nut and said marginal flange confining the sealing disc beneath the head for preventing mutilation 35 thereof.

2. A mending patch including a disc having a circumferentially extending rib spaced from its periphery defining an inner portion and an outer portion for said disc, said inner portion being of 40 greater height than said outer portion, a stud extending through the disc axially of said inner portion and having a headed upper end bearing against the outer face of the disc and surrounded by the rib, a nut on the stud and a sealing disc 45 carried beneath the disc about said stud and being adapted for closing an opening to be sealed in a wall when the nut is tightened, said rib providing a reinforcement for the disc and together with said upper and lower portions cooperating 50 for creating a binding action between threads of the stud and nut to hold the nut in a set position and also permitting a greater pressure to be exerted upon the outer rim of said disc whereby said sealing disc will be firmly clamped between 55 the head and wall.
